DESIGN FOR A TOP SHELL FOR AN EXPANSIBLE BRACELET OR SIMILAR ARTICLE

Eric G. O. Anderson, Cranston, R. I., assignor to
Everfine Jewelry Manufacturing Company,
Providence, R. I., a corporation of Rhode Island

Application September 25, 1947, Serial No. 141,581

Term of patent 3½ years

(Cl. D45—4)

To all whom it may concern:

Be it known that I, Eric G. O. Anderson, a citizen of the United States of America, residing at Cranston, in the county of Providence and the State of Rhode Island, have invented a new, original, and ornamental Design for a Top Shell for an Expansible Bracelet or Similar Article, of which the following is a specification, reference being had to the accompanying drawing, forming part thereof.

Fig. 1 is a plan view of a top shell for an expansible bracelet or similar article embodying my new design, and

Fig. 2 is a side elevational view thereof.

I claim:

The ornamental design for a top shell for an expansible bracelet or similar article, as shown.
